UNITED STATES PATENT OFFICE

CHARLES A. UPSON, OF LOCKPORT, NEW YORK, ASSIGNOR TO THE UPSON COMPANY, OF LOCKPORT, NEW YORK, A CORPORATION OF NEW YORK

PLASTER WALL SURFACE

Application filed January 17, 1929. Serial No. 333,150.

My present invention relates to building material, and more particularly to plaster wall surfaces and a method of making the same whether the plaster is applied after the 5 rest of the wall is in place, or whether it is desired to first apply the plaster as an outer finishing surface to a ready-to-apply wallboard, and the invention has for its object to provide an improved structure of this character 10 which can be rapidly and cheaply produced; which will have higher wearing and insulating qualities, and in which, particularly, the plaster surface will be intimately and effectively locked to the supporting body.

15 To these and other ends the invention resides in certain improvements and combinations of parts, all as will be hereinafter more fully described, the novel features being pointed out in the claims at the end of this 20 specification.

In the drawings:

Fig. 1 is a perspective view of a fragment of a wallboard provided with a plaster surface constructed in accordance with and illustrating one embodiment of my invention, several elements composing the same being shown cut away from each other in different parallel planes to better illustrate the composite makeup;

Fig. 2 is a section through the board shown in Fig. 1;

Fig. 3 is a view similar to Fig. 1 of a modified form of board, and

Fig. 4 is a section through the board shown 25 in Fig. 3.

Similar reference numerals throughout the several views indicate the same parts.

A preferred form of my new wall surface or wall board and the method of producing 30 the same involves the use of the invention disclosed in the United States patents to Howard F. Weiss et al, No. 1,628,206, dated May 10, 1927, entitled "Molded product and process for its manufacture", and Kemper 35 Slidell, No. 1,655,714, dated January 10, 1928, and entitled "Machine and method for making wallboard" to which reference is suggested. It will be understood however, as indicated by the claims, that my invention is not 40 limited to the operation, materials, and con-

struction therein disclosed. Briefly these patents explain the making of a wallboard for building and similar purposes by a method in which a plastic intumescent body of material having as its principal ingredients a 55 solution of silicate of soda mixed with an inorganic filler such as dolomitic limestone ground to a powdered fineness is introduced between two heavy paper liners and then passed between the confining walls of opposed heated platens, whereby the material is puffed into a highly cellular sheet with smooth flat paper surfaces. When the sheet is hardened by further heat treatments and drying it is transformed into a rigid coherent 60 mass having great insulating qualities and the cells of which are larger or smaller according to the proportion of the component 65 elements employed.

In the practice of my present invention, 70 I prefer to use this method arranging to produce a relatively large cellular structure in the intumescent inorganic material, but in one embodiment of my invention, I use only one of the paper liners described in Patent 75 No. 1,655,474, aforesaid, and referring to Figs. 1 and 2 in which this embodiment is illustrated 1 indicates the heavy paper liner, and 2 the intumescent body which has been caused to adhere thereto firmly by the puffing process. It will be seen from an inspection of Fig. 1 that the outer face of the body 2 opposite to that which is attached to the paper liner or backing 1 has a roughened irregular pitted surface represented by the 80 cells which are only partly formed in the body of the material and open on that surface. In the further practice of my invention I apply to the surface a layer 3 of ordinary plaster in the plastic state by smearing it over and working it into the same giving the exterior the usual smooth or any preferred decorative surface. The soft plaster permeates the open surface cells of the body 2 and becomes locked 85 therein due to their irregular conformation, as clearly shown in Fig. 2. This may be done in the production of the wallboard before it is applied to the wall, or a wallboard may be prepared consisting only of a backing 90 1 and the body 2 which, after its application 95 100

to the wall may receive the plaster coating or surfacing 3 as before.

Figs. 3 and 4, as before stated, illustrate another method of producing the article which is somewhat better adapted to the process of the patents referred to if this is to be utilized in making up the cellular body element. In drawing the backing liner 1 and the body 2 through the heated platen difficulties may arise owing to a tendency on the part of the intumescent plastic 2 to stick to the heated platens. To avoid this I may use, in addition to the heavy liner 1 a very light tissue-like liner 4 on the opposite or outer face, the same being composed of the very thinnest paper that can be fed to the machine. When, however, the plaster body 3 is applied as before to furnish the desired surface, this tissue 4 becomes saturated by the wet plaster and is destroyed as a liner permitting the plaster in its plastic state to permeate the cells and lock into the same as before.

It will be understood that my reference to the two existing United States patents aforesaid is merely an illustration of one manner of accomplishing the desired results of the present invention in the production of a suitable cellular body on a backing to take the plaster surface, and it is to be understood further that, in the broad aspects of my present invention, this body element may be produced in other ways.

I claim as my invention:

1. A method of making plaster wall surfaces which embodies applying a hard adhesive cellular mineral composition to a relatively heavy paper liner at the same time applying a thin tissue-like liner to the opposite side of the cellular body and then applying a coating of plaster in a plastic state to the outer tissue and working it therethrough so that it permeates the cells and is locked to the cellular composition, the tissue liner being softened and destroyed as such by the wet plaster.
2. A method of making plaster wall surfaces which embodies introducing a plastic intumescent body containing silicate of soda and a mineral filler as its main ingredients between a relatively heavy backing sheet or liner and a relatively thin and tissue-like liner, puffing the intumescent body by heat while suitably confined to form a cellular body adhering to the liners, hardening the same, and applying a coating of plastic plaster to the outer tissue liner and working it through the same so that it permeates the outer cells of the cellular body and is thereby locked thereto, the tissue liner being softened and destroyed as such by the wet plaster.

CHARLES A. UPSON.
